APPARATUS FOR APPLYING PHOTOGRAPHIC EMULSION UPON STATIONERY AND THE LIKE

Orville R. Betts, John W. Nevius, and Wilhelm Petrus Hendrickson, Long Beach, Calif., assignors to Zenith Progressive Photography Inc., Long Beach, Calif.

Application July 18, 1938, Serial No. 219,786

1 Claim. (Cl. 91—10)

Our invention relates to the application of an emulsion substance upon the paper surface and more particularly to devices and special apparatus which are used for automatically treating the paper surface or a portion thereof with said emulsion, so that said paper, after drying, may be used for printing thereon special designs, pictures or indicia, such as may be found useful in stationery, for personal or individual use, or in printing designs for commercial advertising.

Manifestly, an object of our invention, is to provide a machine or an apparatus, which may be of simple construction and adapted for semi-automatic operation, said apparatus being adapted for carrying the paper in single sheets, or, in folded or roll form, and allowing it to pass over a suitable emulsion applicator, in form of a roller, which will quickly apply said emulsion thereon and immediately thereafter eject said paper into a suitable rack, so as to allow the coated surface to be dried, in readiness for printing.

One of the main objects of our invention is to provide said apparatus or a machine with a set of suitable rollers, which are positioned in a close proximity to each other and running parallel with each other, one of said rollers having a suitable lever member attached to its shaft for controlling its position in relation to the other roller, so that it may be continually or intermittently immersed in a suitable tank member containing said emulsion and therefore causing said roller to apply said substance upon the paper surface, by bearing upon said paper surface against the other roller, also, having a suitable gauge associated therewith for controlling thereon the thickness of the applied emulsion application, as in practice may be most desirable.

Another object of our invention is to provide said machine with a set of conically grooved pulleys, having a drive arranged for facilitating the diversified speeds of said machine, also having a pair of said pulleys so arranged and connected to a suitable roller rotation control lever member, whereby in operation, an intermittent action of a short or longer duration may be had, so that the entire paper surface or any desired portion thereof, or any particular spot on the paper surface, may be coated or treated with emulsion for whatever purpose it may be required.

Further object of our invention is to provide said machine with an electrically controlling member, which may be in a form of a solenoid and which, in operation may be so arranged, whereby the application of the emulsion upon

the surface of the paper, may be had at any desired spot or place and in addition thereto, having a suitable feed controlling member, whereby the feed and the speed of the paper passing therethrough may be constantly regulated.

Further objects and advantages of our invention as will hereinafter more fully appear, we attain by the construction herein shown on the drawing and described in the specification, forming a part of our application.

Reference is had to the accompanying drawing, in which the similar reference characters denote the similar parts.

In the drawing:

Fig. 1 shows the plan view of the machine, 15 showing the position of the feed and emulsion applicating rollers, the application control and the feed pulleys connected to the drive.

Fig. 2 shows the front elevational view of the machine, taken from the Fig. 1.

Fig. 3 shows the diagrammatical view of the machine wiring diagram, and the solenoid control associated therewith.

Fig. 4 shows the enlarged front elevational view of the switch used in the machine for operating 25 and controlling the solenoid of the machine.

Fig. 5 shows the perspective view of the paper, showing the emulsion applied to its surface.

Fig. 6 shows the transverse cross-sectional view of the paper taken on the line 6—6 of the Fig. 5.

Describing our invention more in detail, in its broader aspect, said invention comprises a suitable frame member, generally designated by numeral 2, which is mounted upon a stand 4 and having a suitable driving mechanism 6, as 35 shown.

Said frame member 2, comprises a pair of upright members 8 having a cross member 10 upon which the roller bearings 12 are mounted, and which are for the purpose to hold in place a top 40 roller 14 suspended upon a shaft 16, which is held in engaged position in the said bearings 12.

The inner upright members 18, at the underside of the said cross member 10, are provided with a suitable pivot shaft 20, upon which a pair 45 of levers 22 are pivotally mounted, of which, one end thereof is provided with a roller shaft 24 having a spreading roller member 26 positioned thereon, as shown, while the other end of the said lever 22 is provided with a cam section 30, the 50 purpose of which will be presently described.

The said spreading roller member 26 may, if so desired, be positioned directly over the tank member 32, wherein the paper coating emulsion is placed, said tank member 32 having a suitable 55

trough 34 adapted for controlling the flow of the solution or emulsion into the center and beneath the said spreading roller 26, and also for preventing an accidental spilling of the said solution, further, for the purpose to drive the said roller 14 and the spreading roller 26 in proper direction, the ends of the said shafts are provided with suitable grooved pulleys 36 and 38 respectively, having a cross belt 40 associated therewith, which causes said rollers to operate in the same peripheral direction, also, in order to rotate said rollers at a desired speed, the opposite shaft end 42 of the shaft 16 is provided with a driving pulley 44, which is driven by means of a transmission pulley 46 and interconnected by means of a cross belt member 48, as shown.

Said transmission pulley 46 is mounted upon a suitable shaft to which a speed reduction pulley 50 is connected and which are operable by means 20 of a belt 52 connecting the motor driving pulley 54 of the electric motor 56.

It may be noted, that the said set of driving pulleys, may, if so desired, be changed, so as to increase or decrease the speed of the roller 14, 25 which governs the speed of the paper passing thereunder and co-relatively controlling the speed of the spreading roller member 26.

In order to feed the paper through the machine in short strips and widths, or, in long strip out of 30 a suitable roll, the said machine is provided with suitable guide tapes 58, which are arranged in pairs of which one set of said guide tape 58 entrains the rollers 14 and 62 only, while the other set of guide tape 58 entrains over the rollers 60 35 then under and over the roller 14 entraining the pulleys 64, 66 and 68, finally returning to the rollers 60, as shown, thus allowing the paper to be guided continually, under and over the roller 14, when in operation.

40 For the purpose to actuate the pivotally mounted spreader roller 26, the lever extension 28 provided with the cam section 30 is adapted to engage the draw bar 70 which is operable by means of the magnetic influence of the solenoid member 72.

45 Said solenoid 72 is influenced by the electric current passing therethrough when the switch 74 is closed, and which is automatically closed or opened whenever the switch finger member 76 makes one turn or one revolution, so that, by 50 changing the belt member 78 to any of the grooves of the said pair of grooved pulleys 80, then their rotation or speed and the opening or closing of the switch 74 in relation to the speed of the roller 14, may be regulated, consequently actuating the 55 solenoid 72, which will cause the draw bar 70 to bear against the cam section 30, and therefore pivoting the spreading roller 26 in and out of the said tank 32 and against the said roller 14, or against the surface of the paper passing thereover.

60 By the arrangement of the mechanism herein described, an intermittent application of the emulsion, upon the paper surface may be had, further, it may be noted, that the driver of the

grooved pulleys 36 may be changed at the main transmission shaft 82, in order to provide a slower or faster movement of the spreader roller 26 without greatly impairing the general driving members of the machine.

5 In the Fig. 3, the wiring diagram shows the source of power G from which the lead wire 84 connects the driving motor M and the lead wire 86 connecting the contact switch 74, and the return lead wire 90 from the motor M connects the solenoid member 72 at one end while the lead wire 92 completes the circuit between the said solenoid 72 and the said contact switch 74; then, in order to provide a complete circuit for the wiring, a lead wire 94 connects the wire 90 having a starting 15 switch 96 from which the lead wire 98 leads to the source of power G, as shown.

We claim as our invention:

In the apparatus of the class described adapted for applying an emulsion upon the paper surface, 20 comprising, a stand, a frame member positioned upon said stand, a drive member associated with said frame and positioned upon said stand, a roller member rotatably mounted in said frame and operable by the said drive member, said roller 25 member having a guiding tape disposed thereover which extends over and under the said stand and said frame for forming a continuous belt adapted for guiding the said paper into and out of the said roller member, an emulsion spreading roller member 30 revolvably disposed beneath and driven by the said roller member positioned thereabove, a tank positioned underneath the said spreading roller for dispensing the said emulsion therefrom, a pair of pivot bar members pivotally connected to the 35 said frame for holding the said spreading roller in place and for immersing it in said emulsion, an extension bar extending out of one of the said pivot bar members, a cam member positioned at the end of the said extension bar, means 40 connected to said frame for engaging the said cam member for controlling the position of the said spreading roller within the said tank and beneath the upper roller member, a pair of grooved pulleys associated with the said frame and operable by the 45 said drive member, a contact finger member connected to the shaft of one of the said grooved pulleys, a solenoid member connected to said frame energized by the electric current passing therethrough, a switch member positioned in close 50 proximity to and operable by the said contact finger member for actuating said solenoid at each or every revolution of the said grooved pulley, and a draw bar member associated with the said solenoid and the said cam of the said extension bar 55 for intermittently and pivotally actuating the said spreading roller into and out of the emulsion positioned within said tank and upon the paper surface passing thereover, during the operation of the apparatus.
